UNITED STATES PATENT OFFICE

WOLFGANG D. RICHTER, OF PHILADELPHIA, PENNSYLVANIA, ASSIGNOR TO WILDMAN MFG. CO., OF NORRISTOWN, PENNSYLVANIA, A CORPORATION OF PENNSYLVANIA

FULL FASHIONED KNITTING MACHINE

Application filed January 30, 1930. Serial No. 424,651.

The invention concerns mechanism for rocking the needle bar of full fashioned knitting machine or cotton frames during the introduction of the extra yarn for reinforcing and particularly during the making of tapered reinforced areas in the stocking for the high splice.

The invention also includes safety mechanism whereby during the time that the narrowing actions are performed and the main cam shaft is shifted the means for automatically adjusting the needle carrying bar will be thrown out of action.

The invention includes various other features which will be clear from the accompanying description and the appended claims.

The accompanying drawings show in:

Figures 1 and 1a are front views of so much of a full fashioned knitting machine as is necessary to illustrate the embodiment of my improvement thereon. These two figures are to be regarded as one view. Fig. 1a belongs at the right of Fig. 1.

Figs. 1b, 1c and 1d show details of the mechanism of Figs. 1a and 2a.

Figs. 2 and 2a are plan views of parts shown in Fig. 1, Fig. 2a belonging at the right of Fig. 2.

Fig. 3 is a transversed section of the machine from front to rear.

Fig. 3a is a view taken transversely of the cam shaft showing more in detail a group of mechanism of Fig. 3.

Fig. 4 illustrates different forms of cams for rocking the needle bar to get different shapes of reinforced areas.

Fig. 5 is a detail view of a pin drum and the part for which it acts as a stop.

Fig. 6 is a detail view looking from the right of Fig. 1a.

Fig. 7 is a face view of the wing cam and associated parts.

In the drawings the needles 1 are mounted as usual in a bar 2 carried by a yoke member 3 pivotally mounted at 4 to an arm 5 of a lever fixed to the needle bar rock shaft 6, the other arm 5a of said lever (shown broken away in Fig. 3) extending down to be operated by a cam (not shown) on the cam shaft

7, all as in ordinary practice. This mechanism gives to the needle row its up and down movement as is well known. The needles are also given as usual a rocking movement about the pivot 4 and for this purpose the yoke 3 which supports the needle bar is given a swinging movement by a lever 8 fixed to the presser shaft 9 suitably mounted in the frame. The lever 8 depends from the presser shaft and is operated by a cam on the shaft 7, and for this purpose the lever arm is provided with a roller 10 to bear on the cam on the main cam shaft 7. The lever 8 connects with the yoke 3 by an arm 8a pivoted to the lower end of the yoke at 3a. The arm has a handle 8b by which it may be lifted to disengage the arm from the pin 8c to thus allow the yoke 3 to be turned about its pivot 4 by moving the handle backward for swinging the needle row towards the front of the machine. This rocker mechanism operated by the cam 10a and roller 10 also is of the ordinary and well known form and is for the purpose of pressing the needle beards in the formation of the stitches, there being provided as is well known, a presser bar against which the beards are pressed as a result of that part of the rocking movement which takes place towards the rear of the machine.

It will be understood that the rocking movement with which this invention is concerned is for the purpose of changing the position of the needle row in respect to the sinkers for drawing longer stitches during reinforcing is quite independent of the rocking movement for pressing just mentioned.

When the tapered high splice is to be produced provision must be made for forming longer loops by moving and holding the needle bar relative to the sinkers to accommodate the additional yarn i. e. the splicing yarn and as the reinforced area is tapered, and the length of the successive spliced courses varies in accordance with the pattern, it becomes necessary to hold the needle bar with the row of needles in the adjusted position for varying lengths of time.

In the case of making the high splice of upwardly tapered form the lengths of the spliced portions of the courses increases with

the succession of the courses and hence the length of time that the adjusted position of the needle row is maintained for getting longer loops must also increase with the succession of courses, or substantially so.

5 In making the high splice therefor the loop lengths must vary during one course because the loops must be longer in the reinforced portion at the heel tabs than at the center portion of the fabric between the heel tabs and as above stated, where the reinforced area gradually widens as the knitting proceeds the proportion of long loops in the successive courses must increase.

15 I show at 11 the regulating rock shaft which has an arm 12 extending up therefrom carrying a pin 13 to bear on the rear edge of the lever arm 8 for removing the lever arm from the influence of the cam 10a on the cam shaft and for swinging the needle bar into position for the formation of longer loops by the act of the sinkers sinking the yarn between them. This swinging movement of the needle bar for getting longer loops is therefore towards the sinkers or in other words, towards the rear of the machine.

30 In order to control this rock shaft 11 so that its arm 12, 13 will hold the lever 8 forwardly for varying periods corresponding to the varying widths of the spliced area, I employ a wing cam on the cam shaft 7, the two wings 14 of which correspond to the two spliced areas above the heel tabs, and the space between these wings corresponds to the plain or non-reinforced portion of the fabric at the center of the fabric, i. e. the portion that is to form the instep. The wings 14 are tapered to correspond with the shape of the areas to be reinforced.

35 40 Cooperating with this wing cam is a roller 15, shiftable along a rod 16 extending parallel with the cam shaft and carried by a yoke 17 fixed to the regulating shaft 11. The roller is shifted automatically by a fork 19 engaging an annular groove in the hub of the roller.

45 The fork 19 is fixed to a rod 20 extending lengthwise of the machine and guided in suitable brackets as 21. This rod is pressed 50 rightward normally by a spring 20b bearing on a collar 20a at one end and the bracket 21 at the other end. The position of the shifting roller when the reinforcing of the area of varying width begins, is at or near the small end of the tapered wings 14 i. e. towards the right in Figs. 1 and 2, and this corresponds in the fabric to the upper end of the upwardly tapered high splice. While this narrow portion of the cam wing 14 is acting on the 55 roller 15 the pin 13 of the regulating arm 12 will be holding the lever arm 8 forwardly so as to adjust the needle row rearwardly for the making of longer loops to accommodate the extra yarn being knitted in. As 60 65 the spliced portion of the successive courses

increases in length, the roller 15 will assume positions step by step towards the wider or base portions of the cam wings 14, i. e. the roller will be moved step by step leftward in Figs. 1 and 2.

70 For determining these different positions of the roller 15 i. e. for causing it to assume positions step by step towards the left, I employ a pattern drum 22 consisting of a wheel or disc having a series of pattern pins 23 75 extending from its side face parallel with the cam shaft. These pins are successively of different length. Starting with a short pin, the next adjacent pin in the circular row is a little longer than the first, the next is a little longer than the second and so on throughout the circle of pins, the pattern face provided by the ends of these pins being thus in conformity with the desired gradually widening shape of the reinforced area.

80 85 This drum is rotated step by step by pawl and ratchet mechanisms shown generally at 24. The pawl is carried by a rocker arm 25 operated by a link 26 from a rocker lever 27 pivoted to bracket 27a having a roller 28 operated by a cam on the cam shaft.

90 95 This roller 28 is shiftable into and out of line with the cam 28a which operates it. This shifting is done by a forked arm or controller 28b attached to a rod 32 operated by a lever 33 from buttons 37 on an endless pattern chain 35.

A detent 29 holds the pattern drum in any position to which it is operated.

100 105 The ratchet wheel arrangement consists of two wheels, one 24a having regular teeth and the other 24b having every other tooth a deep tooth so that only when the pawl drops into the deep tooth will it engage the regular ratchet and turn the drum. The cam shaft 7 makes one revolution for each course. The pawl 24 is operated once for each revolution but because of the ratchet arrangement the drum will be moved only one step for two revolutions of the cam shaft, 110 and hence once for each two courses.

115 120 The drum by its pins as above stated determines the positions of the shifting roller 15 relative to the tapered cam wing.

125 130 For this purpose the rod 20 has a stop 20a fixed thereon to come against the pattern pins 23 as they are brought around by the drum into position to be contacted by the stop 20a when this moves with its rod 20 rightward, under the action of the spring 20b.

This spring is arranged between a collar 20a on the rod and one of the brackets 21. This rod 20 must first be moved leftward in order to free the stop 20a from the stepped formation provided by the pattern drum pins 125 for the purpose of allowing the drum to be turned step by step to bring its various stop pins into line with the stop pin 20a and then the rod is moved rightward until stop pin 20a comes against the pin on the drum. The 130

leftward movement of the rod just mentioned above is accomplished by a bell crank lever 20c Figs. 1a and 2a pivoted to a bracket 20d and having its horizontal arm 20e underlying a lever 20f pivoted to the frame at 5 20g. This lever has a roller 30 operable by a cam 29x on the cam shaft 7 when shifted into line therewith, and when operated the lever 20f will depress the horizontal arm of the bell crank lever 20c and thus shift the rod 20 leftward. This will, of course, momentarily displace the shiftable roller 15 along the wing cam 14 but during the time that this 10 displacement is taking place the pin drum 22 will be advanced one step to bring its next longer pin into line with the stop 20a ready to arrest the rod 20 when it again moves rightward and this stopping will set the roller 15 in its new position towards the left, and if we 15 are making a widened high splice the new position of the roller will be one step towards the wide end of the tapered wing cam 14.

The operation is so timed that the shifting of the roller 15 takes place when the gap 20 between the wings 14 comes opposite the roller, that is, the gap that exists between the straight edges of the cam wings, this gap being wider than that between the tapered edges.

30 It will be seen from the above that the controller rod 20 will be given a reciprocating movement and during the stroke leftward the pin drum will be rotated to bring the next pin in line to stop the rod on its rightward stroke with the roller 15 set in proper position.

In order to bring the lever 20f into action as just described for the making of the high splice the cam roller 30 is shifted from neutral position rightward into line with cam 29x by a fork or controller arm 31 fixed to the rod 32 extending along the front of the machine and connected at its left end with the bell crank lever 33 pivoted to a fixed bracket at 34.

This bell crank lever overlies the endless chain 35 which chain together with its drum 36 and driving ratchet 37x is well known standard equipment, as well as the cam operated pawl 37a for operating said ratchet. The pattern chain for purposes of my invention has buttons as 37 thereon adapted to engage and lift the horizontal arm 33a of the bell crank lever so that its vertical arm 55 33 will move the rod 32 rightward and thus cause the fork 31 to shift roller 30 into line with the cam 29x to bring on the operation of the rod 20 to set roller 15 for making the high splice.

60 It will be understood that the chain brings on the operation of the high splice mechanism including the movement of the pin drum 22 for which latter purpose the rod 32 has the fork 28b for shifting the roller 28 into line 65 with its operating cam 28a.

The rod 32 is normally pressed to the left by a spring 32x so that the high splice mechanism above described is out of action. The lever 33 when operated by the chain sets the controller rollers 28, 30 and 30x in line with their cams. The latter roller 30x is operated to feed an upper drum 22x step by step through lever 39, rod 40, lever 41, link 42 and pawl and ratchet device 43. This upper drum provides the variable stops for the yarn carrier rods indicated generally at y these being the same as are usually employed in this type of machines.

70 They carry the yarn feed fingers which traverse the rows of needles to supply the yarn thereto. This upper drum has pins 23x of progressively different lengths, to accord with the tapered area which is to be reinforced. The upper drum is double in form having besides the set of pins 23x the ends of which face towards the left, another set 75 23y, the ends of which face towards the right. The set of pins 23x act as stops for the rightward movement of the yarn guide carrying rods y so as to define the right hand edge 80 of the reinforced area. For this purpose they coact with the usual stops on the carrier rods, one of which is indicated at y1, Fig. 1, while the other set of stop pins 23y coact with the 85 stops on the carrier bars y, one of which is indicated at y2.

90 These stops 23y and y2 limit the leftward movement of the yarn guides and thus define the lefthand edge of the reinforced area.

95 For shifting the roll 30x into and out of line with the cam 30y see Fig. 3 on the cam shaft 7, I employ an arm 32x fixed to the shifting rod 32 and having a fork to engage a collar or grooved hub on the roll 30x.

100 As is well known the cam shaft 7 is shifted towards the right during the narrowing operation so as to carry the knitting cams out of line with their respective rollers. In my improvements this shifting of the cam shaft rightward brings a cam 29a into line 105 with the roller 30 and the lever 20f will be depressed by this cam and thus the bell crank 20c will be operated to a degree sufficient to throw the roller 15 at the wing cam 14 leftward beyond the range of this cam so that during the narrowing operation there will be no contact of the wing cam 14 with the roller 15 and the needle bar will not be moved backward from its normal position, this mechanism furnishing a safety device to insure that during the narrowing operation the needle bar will not be rocked out of its normal position, and the narrowing operation, involving the transfer of stitches from needle to needle will not be interfered with.

110 115 120 125 After the narrowing operation has been completed the main cam shaft is shifted leftward so that the knitting cams are again brought into action. This shifting of the main cam shaft releases roller 30 from con-

trol by the cam 29a and then the lever 20f, lever 20c and rod 20 will restore to normal or inactive position and the shifting roller 15 will be set out of the range of movement of 5 the tapered wing cam while ordinary knitting is being performed and until reinforcing of the fabric is again proceeded with.

In Fig. 4 I show two forms of the wings of cam 14. The wing 14a will cooperate with 10 the pin drums and yarn carrier stops which will make a vertical edge at one side of the reinforced area and an inclined edge at the other side. If the reinforced area is to have both edges inclined in respect to the center 15 line of the goods to provide a high splice tapered equally then the wings of the cam 14 would be like that indicated at 14b.

I claim:

1. In a full fashioned knitting machine 20 and in combination, a needle carrying bar, means for adjusting said bar automatically to a rearward position for making longer stitches during reinforcing, including a rotary cam and a member operable thereby and 25 connected with the needle bar, means for rotating said cam, means for automatically changing the relative positions of the said member and cam, consisting of means for reciprocating said member and a rotary cam 30 for stopping said member variably on one stroke, splicing yarn fingers, reciprocating carriers therefor, cam means for variably arresting the carriers, with means for automatically rotating the said cam, a controller, 35 and connections therefrom to the member reciprocating means, for bringing the same into action, and to the rotary cam operating means for variably stopping the member and to the rotary cam operating means for variably 40 stopping the yarn carriers for bringing said cams into action, substantially as described.

2. In a full fashioned knitting machine, means for adjusting the needle bar for splicing comprising a cam on the main cam shaft, 45 a roller shiftable lengthwise of the machine along said cam, a rod extending lengthwise of the machine for shifting the roller, a cam on the main shaft, lever means operated thereby for initiating reciprocating movement of 50 said rod, a stop cam for variably limiting the movement of said rod in one direction, means for operating said cam, pattern controlling mechanism for determining the times of operation of said lever means and said stop cam, 55 said main cam shaft being shiftable for narrowing, and cam means on the cam shaft for operating the said lever means and rod for shifting said roller lengthwise of the machine and out of the range of its operating cam 60 when said main cam shaft is shifted for narrowing.

3. In combination in a full fashioned knitting machine, means for rocking the needle bar during knitting of the courses containing 65 reinforcing yarn consisting of a cam, a

member operated by said cam and connected with the needle bar, means for shifting the said member automatically along said cam to hold the needle bar in its rearward position for different lengths of time that said member will be operated by said cam, said shifting means giving to said member a reciprocating movement lengthwise of the machine and automatically operated stopping means 70 which variably arrests the stroke of the member in one direction, substantially as described.

4. In combination in a full fashioned knitting machine, means for adjusting the needle bar automatically for making longer stitches during the knitting of the reinforced part of the courses, consisting of a cam varying in form in a direction lengthwise of the machine, a shaft extending lengthwise of the 80 machine and carrying said cam, a member operated by said cam and connected with the needle bar, means for reciprocating said member lengthwise of the machine, a drum arranged on an axis parallel with that of the cam shaft, said drum having stops arranged annularly about the axis of the drum at different positions lengthwise of the machine for arresting the said member in one direction and with variations in length of stroke and means for giving said drum a 90 step by step movement automatically to bring its stops in position to arrest the movement of said member.

5. In combination in a full fashioned knitting machine, a needle bar, means for rocking said needle bar during the knitting of courses containing a reinforcing yarn, comprising a main cam shaft, a cam thereon varying in form in a direction lengthwise of the said shaft, a regulating shaft with a connection between the same and the needle carrying bar, a yoke on the regulating shaft, a roller shiftable on said yoke in a direction lengthwise of the cam shaft, a rod extending and reciprocal in a direction lengthwise of the cam shaft, a member on said rod connected to the roll for shifting it, means for automatically reciprocating said rod lengthwise, a rotary step by step drum with means for operating it automatically, said drum having stops annularly arranged and at different positions along the machine, said stops arresting the strokes of the rod in one direction and to locate the roll at different points along the cam to hold the needle bar in its rearward position for different lengths of time to accord with the varying width of the reinforced area, substantially as described.

6. A full fashioned knitting machine having in combination a needle carrying bar, means for moving said bar into position to produce longer stitches during the reinforcing of the fabric said means including a cam, and a member operated thereby and shiftable along the cam to be variably controlled there-

by, means for so shifting said member, a main shaft shiftable lengthwise to bring the narrowing cams into action and to eliminate the action of the knitting cams, and means for eliminating the operation of the needle bar moving mechanism, said last mentioned means being normally out of service and brought into service by the shifting of the main cam shaft for narrowing, said eliminating means shifting the said cam operated member away from operative relation to the cam substantially as described.

7. A full fashioned knitting machine, having a needle carrying bar to be adjusted to or set in rearward position for making longer stitches during reinforcing, a cam on the main cam shaft for shaping the reinforced area and a member operated by said cam for setting the needle bar in its rearward position, said member having relative shifting movement lengthwise of the machine to bring different portions of said cam into action on said member, a rod extending lengthwise of the machine for effecting said adjustment, means for operating said rod, a cam on the cam shaft for operating said means, pattern means including a controller device for bringing the rod operating means under the influence of said last mentioned cam, said main shaft being shiftable lengthwise for bringing into action narrowing cams and throwing out of action knitting cams and a cam for giving the rod operating means a movement to eliminate the action of the shaping cam on the member to eliminate movement of the needle bar during narrowing, substantially as described.

8. Apparatus according to claim 7 in which the movement of the rod under the action of the cam on the main shaft carries the shiftable member out of range of the shaping cam, substantially as described.

9. In a full fashioned knitting machine and in combination, a needle carrying bar, means for adjusting said bar automatically to a rearward position for making longer stitches during reinforcing including a cam and a member operable thereby and connected with the needle bar, said member being shiftable relative to the cam, a rod extending along the machine for operating said shiftable member, a lever connected to the rod, for operating it lengthwise, a cam on the main cam shaft, a member shiftable to and out of position to be operated by said last mentioned cam and when operated transmitting movement to said lever, a pattern chain and a rod set by said chain, and connected to said shiftable member last mentioned, substantially as described.

10. Apparatus according to claim 9 in which the last mentioned shiftable member is carried by a lever pivotally mounted and extending transversely of the machine, and said lever operating the first mentioned le-

ver in a direction lengthwise of the machine, substantially as described.

11. In a full fashioned knitting machine, a needle carrying bar, means for setting said bar in position to make longer stitches during reinforcing including a cam of varying shape in a direction lengthwise of the machine, a main cam shaft carrying said cam, a roller shiftable along the cam lengthwise of the machine, means operated by the roller connected with the needle bar, a rod extending lengthwise of the machine for shifting said roller, a cam on the main shaft, means operated by said cam for moving said rod lengthwise including a controller to determine when said last mentioned cam will operate said means to move said rod, a pattern chain, means operated by said chain including a rod extending along the machine for operating said controller, substantially as described.

12. In combination in a full fashioned machine, a needle bar, a cam, a member to be operated by said cam and shiftable relative to said cam, a connection between said member and the needle bar for setting the latter in position for making longer stitches when reinforcing is to be done, mechanism for shifting said member, including means for reciprocating said member, stop means for varying the stroke of said member in one direction, said stop means having a plurality of stops to be brought in succession for action, a cam on the main shaft with a connection operated thereby for giving the stop means a step by step action, a controller for determining the periods of the step by step action of the stop means, a pattern chain and means for operating the controller therefrom.

13. Apparatus according to claim 12 in which the reciprocating means for the shiftable member is operated by a cam on the main shaft, a controller for determining when said cam will operate said reciprocable means, a rod extending along the machine and operated from the pattern chain for setting said controller in operative position, said rod also setting the controller of the stop means, substantially as described.

14. Apparatus according to claim 3 in which the means for shifting the said member is operated by a cam on the main shaft and together with said cam is located at one end of the machine and pattern mechanism for controlling the times at which said shifting means will operate, said pattern mechanism being located at the other end of the machine, substantially as described.

15. In combination in a full fashioned knitting machine, means for automatically setting the needle carrying bar rearwardly during reinforcing to make longer stitches, said means including a cam and a member shiftable along the same to be operated

- thereby for different length periods of time, a rotary drum having stops to determine the shifted position of said roller, a yarn carrier supporting bar for the reinforcing yarn fingers, a stop on said bar, a rotary drum having annularly arranged but axially differently disposed stops to coact with the stop on the carrier bar to arrest the same progressively, and means for giving the drums a step by step movement.
- 10 16. A full fashioned knitting machine according to claim 15 in which the drums are operated from cams on the main shaft through pawl and ratchet mechanisms, shiftable controllers to at times transmit power from said cams to said mechanism, a pattern chain and means operated thereby for setting the shiftable controllers in operative position, substantially as described.
- 15 17. In a full fashioned knitting machine, and in combination with the needle carrying bar, means for setting said bars for making longer stitches during reinforcing, including a rotary cam on the main cam shaft of varying shape in a direction lengthwise of said shaft, a member shiftable along the said cam to be operated thereby, a connection between said member and the needle bar for adjusting the latter for reinforcing, means
- 20 for shifting said member including a rotary drum having annularly disposed stops positioned at different points in the direction of the axis of the drum, a rod connected to said shifting member and having a stop to coact with the stops on the drum, means for moving the rod lengthwise of the machine, including a cam on the main cam shaft and a lever operated thereby, a carrier rod for the reinforcing yarn finger, said rod extending lengthwise of the machine, a stop thereon, a stop drum having annularly arranged stops to coact in succession with the stop on the carrier rod, said drum stops being varyingly positioned in the lengthwise direction
- 25 of the machine to vary the length of stroke of the carrier rod to accord with the pattern of the reinforced area, cams on the main cam shaft for operating the drums, a pattern chain, a rod extending lengthwise of the machine, and operated by the pattern chain, and controller means shifted by said rod to render the cams on the main shaft effective or ineffective in operating the two stop drums and the lever which operates the shifting member relative to the cam first mentioned, substantially as described.

In testimony whereof I affix my signature.
WOLFGANG D. RICHTER.
